REGISTER

Loring Pickering Crosman, South Orange, N. J., assignor to Monroe Calculating Machine Company, Orange, N. J., a corporation of Delaware

Original application November 29, 1941, Serial No. 421,016. Divided and this application November 25, 1942, Serial No. 466,936

3 Claims. (Cl. 235—130)

The invention has relation to registers and more particularly to the clutch engaging and digit key latching means of a motor driven registering machine, the present application being a division of application Serial Number 421,016, filed November 29, 1941, relating to operation control mechanism.

The invention consists in the novel construction and combination of parts, set forth in the appended claims.

In the accompanying drawings, illustrating the invention:

Fig. 1 is a vertical section of an adding listing machine embodying the invention, said section being taken through the digit value keyboard.

Fig. 2 is a right side elevation of the operating keys, the sign control slide and associated parts.

Fig. 3 is a detail plan view of the clutch release slide.

Fig. 4 is a detail right side elevation of the quick stroke slide and associated parts.

Fig. 5 is a detail plan view of the operation control slides and associated parts.

Fig. 6 is a right side elevation showing the accumulator meshing means, the slide controlling the digit index bars, etc.

Fig. 7 is a fragmentary bottom plan of the digit value and operating keyboard, showing certain interlock mechanism.

Fig. 8 is a similar view of the operation key interlocks.

Fig. 9 is a detail left side elevation of a portion of the operating train.

Fig. 10 is a right side elevation showing the accumulator zeroizing slide and associated total mechanism.

The invention is shown as applied to a machine similar to that disclosed in United States Patent No. 1,932,013, issued October 24, 1933, to Loring P. Crosman, and entitled "Registers." The printing mechanism illustrated forms the subject matter of an application for patent, Serial Number 421,015 filed November 29, 1941.

In accordance with this disclosure, amounts set up in the digit keys 215 (Fig. 1) are transferred to an accumulator 473, upon operation of the machine, by means of a series of differential actuators 610. These differential actuators are spring operated, and are normally restrained by frame 616. Actuators 610 are formed as three-armed levers, the forward arms thereof having segmental gear teeth for rotating the accumulator wheels; the upper arms being pivotally connected each with a digit index bar 615, and the rearward arms being pivotally connected each

with a type bar 611 of the printing mechanism. The actuators 610 are normally held under restraint of a series of zero latches 214, each zero latch being releasable upon depression of any key 215 in the same column by means of a slide 213. Upon operation of the machine, and movement of frame 616, the released actuators will be rotated counter-clockwise until stopped by contact of a lug of the related index bar 615 with the stem of the depressed key, thereby registering the value of said key in the related accumulator wheel and setting the type bar 611 into position to print the digit.

Addition

15 Addition is effected by the depression of a motor key 114 (Fig. 2), the stem of which is provided with a cam surface 40, acting in the depression of the key to move a slide 41 forwardly, thereby operating a bell crank lever 42 having a roller 43 engaging a notch formed in a spring operated slide 44, illustrated also in Figs. 3 and 4. Slide 44 is provided with a lug 45, which, upon depression of key 114 and operation of slide 44, will engage with the upper arm of a pivoted latch 112, thereby releasing the clutch control lever 106 from said latch, whereupon said lever will be moved counter-clockwise by its spring, an insulation roller 109 on said lever thereupon acting to close a switch 110 in the circuit of an electric motor 100. In this movement the lower end of lever 106 will be disengaged from the tail of a spring urged clutch pawl 103, allowing said pawl to fall into engagement with the driving clutch member 104, driven by motor 100. Pawl 103 is mounted upon a plate 105, this plate being rotated counter-clockwise upon engagement of the clutch. Plate 105 is connected by link 108 with a lever 316, fulcrumed upon shaft 301, rotation of the plate serving to reciprocate said lever, 20 the shaft 301, and a cam 318, which operates to effect reciprocatory movement of frame 616, in known manner.

The wheels of the accumulator 473 are rotated additively upon the return stroke of the actuators 45 610, the timed meshing and unmeshing of the accumulator gears being controlled by mechanism disclosed in United States Patent No. 2,055,623 granted September 29, 1936, to Loring P. Crosman, and entitled "Calculating machine."

50 As shown in that patent, the accumulator pinions 403 (Fig. 1) stand normally in mesh with the segment gears of actuators 610, the accumulator shaft 472 being mounted in guide slots of the machine frame so that the accumulator assembly may be moved radially of the actuators,

to mesh and unmash the pinions 403. As shown in Fig. 6, the shaft 472 is adjusted by means of toggle linkage 10, one member of which is fast upon a rock shaft 2. The linkage is held in either of two adjusted positions by means of a toggle spring 11. Fast upon shaft 2 is a plate 419, having yieldable spring connection 4 with an arm 5 provided with a lateral flange 22, and pivoted at 33 upon said arm is a switch 6, flange 22 and switch 6 lying in the plane of a roller 7 fixed upon lever 316.

In additive operations roller 7 will contact with a cam surface 21 of switch 6 and thereafter with the rear end of flange 22, whereby arm 5 will be raised, thus rocking shaft 2 and linkage 10, to unmash the pinions 403 of the accumulator before the actuators are allowed to move. During the forward movement of actuators 610, arm 5 will be held in raised position by engagement of roller 7 with the lower surface of flange 22. At the end of the forward stroke, roller 7 will lift the forward end of switch 6 away from a lug 20 of arm 5, and will thereafter move out of contact with the switch, which will return into normal relation with the arm. Upon the return stroke of the operating mechanism, roller 7 will engage a cam surface 23 of switch 6, restoring arm 5 and the parts 419, 110 and 472 to original position, remashing the pinions 403 with the segments to effect the registration.

The forward movement of slide 44 to engage the clutch will serve to lock key 114 in depressed position, by engagement of an edge portion of said slide with a shoulder 46 (Fig. 6) of the key stem, thus holding the key in depressed position until restoration of slide 44, as hereinafter explained. Forward movement of slide 44 also serves to lock other operation keys in raised position, adjacent portions of the slide coming into position below the key stems. In order to prevent an erroneous operation of the machine from a rapid or incomplete operation of the motor key, a quick stroke slide 47 is provided (Fig. 4), normally held in rearward position, against the tension of a spring, by engagement of a lug 48 of said slide with the end of slide 44. A bail 49 underlies the stem of key 114, and is displaced thereby when the key is depressed, bringing an edge of the bail into position to engage a shoulder 50 of slide 47. Thus, when key 114 is properly operated, slide 47 will be prevented from moving forward under the influence of its spring, whereas in case key 114 is depressed sufficiently to release slide 44 from roller 43, but is not held long enough to be engaged by slide 44, the restoration of the key by its spring 51 will allow the spring bail 49 to rise out of the path of shoulder 50, and slide 47 will move forwardly. The forward movement of slide 47 will rock a bell crank lever 52 clockwise as viewed in Fig. 4, bringing one arm of said lever into position to be engaged by a shoulder 53 of slide 44, thus locking said slide in partially operated position and leaving latch 112 in engagement with clutch control lever 106. Thus misoperation of the machine will be prevented, and the parts will be held in inactive position until slide 44 is retracted by a manual operation hereinafter set forth.

In machines of this character, erroneous registrations are sometimes made by the failure of the operator to fully depress one of the digit entering keys 215 and according to the present invention means are provided whereby a semi-depressed key will be locked in its semi-depressed position, and whereby under these circumstances

the engagement of the clutch 103, 104 will be prevented.

Each column of digit keys is provided with a latching slide 54 (Figs. 1 and 7), movable forwardly upon depression of a key, by means of a cam surface of the key stem, into engagement with an intermediate locking shoulder 55 or with a full depression locking shoulder 56, slide 54 being held in engagement with one or the other of these shoulders by means of a retraction spring 57. Forward movement of slide 54 upon depression of a key 215 will bring a beveled end of the slide into register with a notch formed in a transverse slide 58, so that if the key is latched in partially depressed position slide 54 will prevent any considerable transverse movement of slide 58.

Slide 58 engages one arm of a bell crank lever 59, fulcrumed upon a frame plate of the keyboard and having link connection 60 with a pawl 61 carried upon the end of a bell crank lever 62 which is also fulcrumed upon the frame plate. A spring 63 normally holds the parts 58, 59, 60 and 61 in position in which the pawl 61 engages a pin 64 fixed in the slide 44, and upon release of said slide pressure will be exerted thereby to move slide 58 toward the left. Thus upon operation of the add key 114, if any of the digit keys 215 are locked in partially depressed position, the slide 58 can be moved only a short distance to the left, and pawl 61, through pin 64, will hold slide 44 in partially operated position, wherein roller 43 will rest on top of the slide, but wherein latch 112 will not be disengaged. In this position of the parts key 114 will be locked down and the other operation keys will be inoperative because of the provision of suitable interlocks, to be described hereinafter, and further because of the locking action of slide 44. Therefore, the machine will remain at rest until the keyboard is manually cleared or until the partially depressed key or keys are fully depressed by the operator. Upon full depression of the keys, slides 54 will be allowed to move rearwardly, into engagement with the shoulders 56 of the keys, freeing slide 58 and the train of mechanism between said slide and the slide 44, whereupon the latter slide will be operated by its spring to disengage latch 112 and effect engagement of the clutch. Slide 44 will also engage a rearward extension of pawl 61, effecting positive restoration of slide 58.

Near the end of the cycle of operation of the machine, and after actuators 610 have been brought to rest, means will be operated for releasing the set digit keys 215 and the operation key, 55 for disengaging the clutch and for restoring the control elements to normal position. For this purpose an antifriction roller mounted on a lever 65 (Fig. 10) will be engaged by a cam projection of plate 105, and rocked clockwise against tension of a spring 66. A lever 67 is connected to lever 65 by a spring 68, lever 67 extending upwardly into the path of movement of the lug 45 of slide 44. Displacement of lever 65 by the cam surface of plate 105 will therefore retract slide 44 to and rearwardly beyond its normal position of rest, this extra rearward movement being utilized to clear the digit keyboard. For this purpose a pin 69 on slide 44 is brought into contact with one arm of a lever 70 (Fig. 7), intermediately fulcrumed upon a frame plate of the keyboard, rocking said lever into contact with a shutter plate 71 (see also Fig. 1) having lugs engaging shoulders of the slides 54. Slides 54 will thus be moved forward, releasing the keys 215 from depressed posi-

tion and allowing them to be restored by their springs 51.

Retraction of slide 44 will also unlock the operation key and will allow roller 43 to fall into latching engagement with said slide.

If repeat operations are to be performed, the operator maintains finger pressure upon the add key 114, whereby roller 43 is held out of engaging position with slide 44, so that when, during the final portion of the cycle, the roller of lever 65 drops from the high point of the cam of plate 105, lever 67 will be moved forwardly and slide 44 released for forward movement, providing for a second cycle of operation of the machine. When key 114 is so held a portion 72 of the key stem (Fig. 6), lying opposite the locking shoulder 46, will prevent retraction of slide 44 rearward beyond normal position, this being permitted by the tensioning of spring 68 and providing for non-clearing of the digit keyboard.

The keyboard may be manually cleared, and any depressed operation key which has been locked because of an erroneous quick stroke operation may also be released by means of a lever 73 (Fig. 10) fulcrumed on the framing of the machine extending through the keyboard plate, said lever being adapted to contact and push slide 44 from operated position to its extreme rearward, keyboard clearing position. Manual release of the lever will permit the spring of slide 44 to restore the parts to normal position.

Subtract and non-add operations

Subtract and non-add operations are performed in response to the depression of a subtract key 274 and a non-add key 275 respectively, these keys controlling the positioning of a slide 74 (Fig. 2), which in turn controls the adjustment of the switch 6. Slide 74 is held normally under the tension of a spring 75 by engagement of the upper end of a lever 76 with a shoulder of the slide, lever 76 being provided with an anti-friction roller normally engaging the high point of the cam portion of plate 105. In the operation of the machine lever 76 will be reciprocated, and slide 74 will be allowed to move forward under the influence of spring 75. In additive operations, however, this forward movement of slide 74 is prevented by engagement of a shoulder 77 of the slide with the bail 49 which has been displaced by the add key 114. There is no shoulder on slide 74 which may contact with the bail 49 of subtract key 274, so that when the subtract key is depressed and the machine operated, slide 74 will move to its extreme forward position. Depression of non-add key 275 will bring its bail 49 into the path of movement of a shoulder 78 of slide 74, to provide for partial forward movement of said slide. Thus slide 74 will be selectively positioned according to the key depressed, the three positions of the slide being transmitted to switch 6 by means of an arm 79, pivoted to the slide, and held in relation thereto by the spring 75, and a link 80 connecting arm 79 with an arm of the switch.

Depression of the subtract key will thus effect rocking of switch 6 clockwise about its pivot point 33, whereby cam surface 21 of the switch will lie out of the path of movement of roller 7. Therefore, upon the forward stroke of the operating mechanism roller 7 will move idly over flange 22, allowing the pinions 403 of the accumulator to remain in mesh with the segments during the subtractive stroke thereof. At the end of the forward stroke roller 7, having momentarily dis-

placed and passed beyond the switch, will be positioned adjacent the surface 34 of the switch, with which it will engage during the return stroke of the operating mechanism, to raise arm 5 and disengage the pinions from the segments before additive movement thereof. During this return movement roller 7 passes beneath flange 22, and near the end of the movement will engage a projection 35 of arm 5, to restore the parts to normal position.

All of the operation keys are identical in construction, and subtract key 274, aside from the adjustment of switch 6, will provide for the same functioning of the machine as in the case of add key 114.

Non-add key 275 will also provide for the same functioning of the machine except that switch 6 will be rocked only sufficiently to bring cam surface 21 parallel with the end of flange 22 of arm 5. This will bring the entire switch below the upper line of the flange, except for a projection of the forward end of the switch above said line. This, however, does not result in any deflection of arm 5, since in the return stroke of the operating mechanism roller 7 will engage a cam surface 23 of the switch, momentarily rocking the same. Therefore, in non-add operations roller 7 will be reciprocated without effecting unmeshing of the pinions 403, and any amounts subtracted from the accumulator wheels by the actuators during the forward stroke of the operating means will be added back during the return stroke.

Total and sub-total

As is usual in machines of this type, totals are printed by disengaging the actuators 610 from their column latches 214, and from the frame 616 and allowing them to move subtractively under the influence of their springs, to rotate the accumulator wheels to zero, in which position the wheels are held by engagement with appropriate stops, after which the cycling of the machine will effect normal operation of the printing means at the end of the forward stroke of the operating means, whereafter frame 616 will pick up and return the actuators to normal position.

These and other special functions are effected upon depression of the total key 278, under control of slide 74 and of other spring slides lying beneath the bail 49 of the operating keys.

Depression of total key 278 will release slide 44 and start motor operation, as previously described for the other keys, and it will also allow full movement of slide 74, to provide for subtractive operation—that is to say, the accumulator pinions 403 will be left in mesh during the zeroizing operation, and will be unmeshed before the additive stroke of the actuators 610 is effected.

The zeroizing of the accumulator wheels is effected by successive operation of the wheels from right to left of the accumulator, as in Patent No. 1,932,013, hereinbefore referred to, this action being controlled by spring operated means. In the present instance, however, it is desired to effect the various adjustments of the controlling mechanisms by power from the motor, and consequently the clutch will be engaged upon depression of the total key, will be allowed a limited driving movement, and then the motor operation will be interrupted to give time for the completion of the zeroizing operation, at the conclusion of which the clutch will be reengaged and the cycle of operation completed. For this purpose a slide 81 (Fig. 10),

which is locked out of operation by the balls 49 of the add, subtract and non-add keys, will be allowed to operate under the influence of its spring 82, said slide having a pivoted link 83 having pin and slot engagement with a latch 84. Upon forward movement of slide 81 (effected upon forward movement of arm 76) link 83, in the movement thereof about its point of connection with the latch, will have its lower end moved downwardly, tensioning a spring 85 which will tend to move latch 84 clockwise about its pivotal support. The free end of latch 84 has engagement with a spring pressed arm 86, pivoted upon the machine frame and having an anti-friction roller engaging the cam surface of plate 105. During the first part of the cycle of the operating means the roller of arm 86 will climb to the high point of the cam, rotating arm 86 clockwise and allowing latch 84 to fall into a notch formed in the upper end of said arm. Arm 86 has a rearward extension 87 which will be held by latch 84 in the path of rotary movement of the clutch pawl 103, engagement of the pawl with extension 87 serving to disengage the pawl from the driving member 104 of the clutch and to hold it in disengaged position.

Slide 81 also has link connection 88 with an arm 134, pivoted upon the machine frame and provided with a finger 133 which will be brought during the movement of slide 81 into contact with the releasing arm 621 of a latch 620, disengaging said latch from a projection 627 secured upon a total segment 618, thereby releasing the segment for operation under the influence of a spring 681. Segment 618 drives a pinion secured on the end of a shaft 607 (Fig. 1), extending across the machine, said shaft being provided with a series of helically disposed pins which will successively trip a series of dogs 617, normally securing the actuators 610 to frame 616. Dogs 617 are also provided with shoulders normally restraining a series of spring pressed stops 613 in negative position. Upon displacement of a dog 617 the related stop 613 will be released, being brought by its spring into the path of movement of a zero stop 457 of the related accumulator wheel. During this preliminary setting of the total controls, the column latches 214 will also be released, in the manner herein-after described, so that actuators 610 upon successive release from the frame 616 will be moved by the springs to rotate the related accumulator wheels to zero.

Upon complete rotation of shaft 607, the projection 627 of segment 618 will contact with a rearward extension of the arm 621, rocking the forward end of said arm out of contact with the finger 133, and allowing latch 620 to move under influence of its spring into position to reengage the extension 627 upon restoration of segment 618. Also, at this time, a pin 89, fixed in segment 618, will engage a depending arm of latch 84, rocking said latch out of engagement with arm 86, whereupon said arm will be rotated counter-clockwise by its spring to move the extension 87 out of restraining contact with clutch pawl 103. Thereupon pawl 103 will reengage with driving member 104 and the operating cycle of the machine will be resumed. During the forward stroke of the operating means, segment 618 will be restored to normal position and reengaged by its latch 620, this restoring means being well known and not illustrated in the present disclosure.

In order that the keyboard may be free for

the setting up of an item during the total taking operation, the index bars 615 are designed to be shifted laterally out of position of engagement with the key stems. A similar arrangement was proposed in United States Patent No. 2,087,182, issued on July 13, 1937 to Loring P. Crosman, entitled "Listing adding machines." However, the means of the present disclosure are of improved construction, and are designed to permit setting 10 of the digit keys during any portion of the totaling operation.

The index bars 615 are supported near their ends in sliding plates 90 (Fig. 5), urged toward the right hand side of the machine by springs 91. The ends of the bars are engaged by a pair of bell crank levers 92, these levers being provided with shoulders engaging lugs 93 of a slide 94. Slide 94 lies parallel to the slides 74 and 81, and is likewise controlled by the operation of lever 76. Bails 49 of the add, subtract, and non-add keys are depressible into position in front of shoulders 95 (Fig. 6) of the slide, to prevent operation thereof. Normally the lever 76, through slide 94, will serve to hold the index bars 615 in normal relation to the digit keys 215 and to the zero latches 214, as seen in Fig. 5. Upon the initial movement of lever 76, permitting forward movement of slide 94, springs 91 will move plates 90 and index bars 615 toward the right, out of position of contact with the keys and also out of contact with the zero latches 214. The plates 90 operate individually, so that there can be no jamming of the parts due to twisting action.

In order that amounts set on the keyboard will not be cleared during the totaling operation, the bail 49 of the total key is provided with an extension 96 (Figs. 2 and 3) which will be held by the key in position to engage a shoulder 97 of slide 44 and prevent movement of said slide rearward beyond its normal position, thus preventing the clearing of the keyboard, as previously explained.

Means are also provided whereby partial depression of a digit key 215 will not prevent a total taking operation, but wherein the parts will remain in position to prevent subsequent operation of the other keys until the keyboard has been cleared or the digit keys properly depressed.

This means is shown as associated with a series of interlocking members between the operation keys 278, 273, 114, 274 and 275 (Fig. 8). The interlocking means comprises a series of plates 98 located each between two adjacent operating keys, and having shoulders engageable by the key stems. As seen in Fig. 6, the portions of the key stems engaged by plates 98 are wedge shaped, so that in the depression of any of the operating keys the two adjacent plates 98 will be moved or held in opposite directions, against the stems of the next adjacent keys.

It will be obvious, therefore, that the plate lying between sub-total key 273 and add key 114 will be moved or held in forward position upon depression of the add key and in rearward position upon depression of the total key 278 or sub-total key 273. A pin 99 is fixed in this plate 98, and projects downwardly into engagement with a slot of the bell crank lever 62 hereinbefore referred to. During operations controlled by the add, subtract or non-add keys the pin 99 will lie in the position illustrated in Fig. 7, and pawl 61 will act to lock slide 44. Upon depression of the total or sub-total key, however, rearward movement of pin 99 will rock bell crank lever 62 clock-

wise, withdrawing pawl 61 from position of contact with the pin 64 of slide 44, so that the slide will not be locked, should a key 215 be partially depressed, until after the release of the total or sub-total key. In a subsequent operation of the machine by key 114, 274 or 275 the pin 99 and bell crank lever 62 will remain in the position illustrated, and tripping of the clutch will be prevented.

Sub-total key 273 operates precisely in the manner of total key 278, except that slide 74 is held in its partially operated position by engagement of the bail 48 with a shoulder 77 of the slide. Thus switch 8 is held in the same position as that assumed in non-add operations, whereby the total, subtracted from the accumulator wheels, is restored thereto during the return stroke of the operating mechanism.

It is intended, when the clutch is disengaged by contact of clutch pawl 103 with lever 106 or with the extension 87 of arm 86, that rebound of the driven parts will be resisted by the rollers of arms 65 and 76, and in order to permit effective checking action the usual heavy spring 140 (Fig. 9), used to assist in smoothing the load on the motor, is provided with lost motion connections with its anchor 141 and with the arm 142 of shaft 301.

I claim:

1. In a motor driven register having a driving train, a clutch in said train, a series of operation keys, digit entering means comprising spring retracted settable keys, and latches engaging the digit keys to maintain them in set position; a normally restrained spring actuated member releasable by any operation key to engage the clutch, spring means operable by the driving train to retract said spring actuated member to and beyond normal restrained position, and means operable by said member in the movement thereof beyond normal position to disengage the key latches and thereby release any set digit keys from set position.

2. In a motor driven register having a driving train, a clutch in said train, a series of depressible operation keys, digit entering means comprising spring retracted settable keys, and latches engaging the digit keys to maintain them in set position; a normally restrained spring actuated member releasable by any operation key to engage the clutch, spring means operable by the driving train to retract said spring actuated member to and beyond normal restrained position, and means operable by said member in the movement thereof beyond normal position to disengage the key latches and thereby release any set digit keys from set position,
- 5 latches engaging the digit keys to maintain them in set position; a normally restrained spring actuated member releasable by any operation key to engage the clutch, spring means operable by the driving train to retract said spring actuated member to and beyond normal restrained position, and means operable by said member in the movement thereof beyond normal position to disengage the key latches and thereby release any set digit keys from set position,
- 10 actuated member to and beyond normal restrained position, and means operable by said member in the movement thereof beyond normal position to disengage the key latches and thereby release any set digit keys from set position,
- 15 said operation keys having stems movable into the path of movement of said member to prevent movement thereof beyond normal position when the operation keys are retained in depressed position during repeat operations.
- 20 3. In a motor driven listing register having a driving train, a clutch in said train, a series of operation keys including registration initiating keys and a total key, and digit entering means comprising settable keys; a normally restrained
- 25 spring actuated member releasable by any operation key to engage the clutch, latches engageable to hold the digit entering keys alternatively in partially set or in fully set position, locking means displaceable by a latch engaged with a
- 30 partially set key to bring an element of said means into the path of effective movement of the clutch engaging member and alternatively cooperating with the actuated clutch engaging member to engage the latches and lock the digit
- 35 entering keys in their fully set and in their unset positions, and means operable by the total key to disable the locking means and prevent cooperation thereof with the latches during a totaling operation.

40

LORING PICKERING CROSMAN.
